[57] **CLAIM**

The ornamental design for a divot tool with hinged magnifier, as shown and described.

DESCRIPTION

FIG. 1 is a front elevational view showing the design of my divot tool with hinged magnifier with the magnifier thereof in its stored position;

FIG. 2 is a rear elevational view thereof;

FIG. 3 is a bottom plan view thereof;

FIG. 4 is top plan view thereof;

FIG. 5 is a left-side elevational view thereof, it being understood that the right-side elevational view appears as a mirror image thereof;

FIG. 6 is a rear elevational view of my divot tool with hinged magnifier shown with the magnifier extended for use;

FIG. 7 is a left-side elevational view of my divot tool with hinged magnifier as shown in FIG. 6, it being understood that the right-side elevational view is a mirror image thereof; and,

FIG. 8 is a rear perspective view showing my divot tool with hinged magnifier with the magnifier in its stored position.
